UNITED STATES PATENT OFFICE.

UPTON J. DUFFIELD, OF WHEELING, WEST VIRGINIA, ASSIGNOR TO WILIAM C. DUFFIELD, OF SAME PLACE.

IMPROVEMENT IN COMBINED STOVES AND BOILERS.

Specification forming part of Letters Patent No. 124,345, dated March 5, 1872.

Specification describing a new and useful Combined Stove and Boiler, invented by UPTON J. DUFFIELD, of Wheeling, in the county of Ohio and State of West Virginia.

The invention is designed for family use, for laundry purposes, for boiling fruit, or as a heater merely, and is adapted to consume as little fuel as practicable. The primary object is to furnish an economical apparatus for independent use for these purposes, so as to avoid the disagreeable consequence of performing laundry work in the kitchen.

The stove comprises a central water-heating jacket and two grates, a permanent one below and a removable one above. The water-heater is connected by pipes with the steam-jacket of a stationary wash-boiler. A fruit-boiler may be placed above the wash-boiler, and is heated by the steam when required for cooking. A cover fits the wash-boiler or the fruit-boiler indifferently. The top of the stove may also serve for heating irons and for other purposes.

Figure 1 is a vertical section, showing the fruit-boiler in position on the wash-boiler. Fig. 2 is a similar section, showing the stove as a heater.

A represents a water-heater, the fuel-chamber forming the body or central part, being surrounded by a water-heating jacket. B is the base of the same; and C, the top thereof; d d', the lids, the latter adapted to fit one in the other and separately removable. c is the fuel-door; and E, the smoke-pipe collar. D D' are grates, arranged respectively in the base B and top C, the latter being removable, as indicated. The water-heater A has tubes a a¹ connecting the hollow walls a² thereof, and communicates with the wash-boiler F through pipes G G. The upper pipe H carries off the steam from the furnace-jacket to the jacket of the wash-boiler. a³ is a discharge-nozzle, used

in emptying the wash-boiler. I is the fruit-boiler. The cover i fits either the wash-boiler or the fruit-boiler. When used as a clothes-boiler, as represented in Fig. 1, the wash-boiler F is partially filled with water, which flows into the space a² between the walls of the heater A and its tubes a¹ a¹. The clothes are then placed in the boiler F, and fire kindled on the lower grate D, the interior walls of the heater and the tubes a¹ a¹ exposing a large surface to the action of the fire, and consequently heating the water with great rapidity. The upper grate D' is removed when the boiler is employed for this purpose, and the fruit-boiler or its lid i used to cover the main boiler. As thus arranged, fruit may be boiled in the said boiler I, the same being heated by steam, while the top of the stove may be used for heating sad-irons. When the main boiler A is not required, fire is made in the upper grate D', the same being placed in position as represented in Fig. 2. The fire-chamber is thus suitably contracted, the apparatus forming a heating furnace. The cover forms a heating-plate for smoothing-irons and other purposes.

I am aware that stoves have been before made with jackets and pipes for heating and circulating water in a stationary wash-boiler. I do not therefore claim this combination.

I claim as my invention—

The combination of the stove, composed of base B, top C, water-heater A, and stationary and removable grates D D', the pipes G G, stationary wash-boiler F and lid i, with or without the fruit-boiler I, constructed and arranged substantially as shown and described, for the purposes set forth.

UPTON J. DUFFIELD.
